DEVICE FOR CHECKING THE COINING OF COINS

Theodore Dietrich, Geneva, Switzerland, assignor to Sodeco, Societe des Compteurs de Geneve, Geneva, Switzerland, a firm of Switzerland

Filed Apr. 3, 1958, Ser. No. 726,137

Claims priority, application Switzerland Apr. 4, 1957

3 Claims. (Cl. 194—97)

For detecting forged coins the identification devices of the automatic distribution machines rely mainly on the coining of the coins as the majority of the coins are provided with a rim which is thicker than their central part.

The device according to the invention enables a very accurate checking of the said coining at relatively low cost.

The said device is characterised in that it comprises a channel for the coins, two pins between which the coins must pass when they fall into the channel, one of the said pins being stationary while the other is mounted at the end of an arm of a first lever, cinematically connected to a second lever an arm of which is provided with a hook projecting into the channel under the said pins so that the motions of the movable pin and of the hook take place in opposite directions and that the hook projects into the channel and interferes with the passage of any coin, the central part of which exceeds in thickness a predetermined value.

An embodiment of the present invention is illustrated in the accompanying drawings in which:

Fig. 1 is a side elevation of the checking device, the channel for the coins being shown in axial section with a genuine coin passing therethrough.

Fig. 2 is a front elevation of the checking device seen from the right of Fig. 3.

Fig. 3 is a side elevation similar to Fig. 1 with one genuine coin and two forged coins inserted in the channel.

The device shown in the drawings comprises an approximately vertical channel for the coins the walls of which are respectively numbered 1, 2, 3 and 4. The wall 1 is provided with two bolts 6 and 9 on which two levers, 5 and 7 respectively, are articulated. Lever 7 oscillates in a vertical plane while lever 5 oscillates in a plane slightly inclined with reference to the vertical.

Lever 5 comprises only one arm the end of which forms a hook 11. Lever 7 comprises two arms, the first being provided with a sharp-pointed screw 10 axially adjustable, while the second is provided with a pawl 8 bearing onto lever 5.

Hook 11 and screw 10 are projecting into an elongated opening of the wall 1. A stationary pin 12 is fixed in wall 2 opposite to the sharp-pointed end 13 of screw 10.

When screw 10 moves in one direction, hook 11 moves in the opposed direction. The length of arms 5 and 7 are chosen so that the multiplication ratio of the movements of screw 10 with reference to hook 11 is 3 or 4.

In the inoperative position of levers 5 and 7, the sharp-pointed end 13 of screw 10 is projecting through the opening of wall 1 while hook 11 is retracted.

When a genuine coin 14 is inserted into the channel screw 10 is first pushed back in the direction of the arrow f_1 by the lower rim of the coin and hook 11 is moved in the direction of arrow f_2 . Once the rim has passed inbetween the pin 12 and the sharp-pointed end 13 of screw 10, hook 11 which has not yet been reached by the rim of the coin resumes at least partially its re-

2

tracted position and frees the channel for the passage of the coin.

When the upper rim of the coin passes between pin 12 and the sharp-pointed end 13 of screw 10, hook 11 is again moved in the direction of arrow f_2 and slows down the speed of the coin without however stopping it.

If a forged coin 19 of a thickness equal to the one of the rim is inserted in the channel instead of a genuine coin, screw 10 remains permanently in its retracted position (see Fig. 3), and hook 11 in its projected position interfering with the passage of the forged coin.

In this case the channel can be cleared by rotation of wall 1 around hinge 18 in the direction of arrow f_4 when a control knob (not represented) is actuated.

The slimmer forged coins 15, which cannot be detected by the device as described, fall directly down, as indicated by arrow f_3 through a narrow slot 16 and cannot pass through branch 17 of the channel and actuate the distribution mechanism of the machine.

What I claim is:

1. A device sensitive to a reduction in the height of rim of coins inserted in automatic distribution machines, comprising two parallel walls defining between them a downwardly sloping channel for the insertion of the coins and of which one is provided with a short longitudinal perforation registering with the path of the coins dropping through the channel, a stationary pin carried by the other wall and facing the upper portion of the perforation in the first-mentioned wall, a first lever pivotally secured to a stationary point outside the perforated wall above the perforation on the side of the wall facing away from the channel, said lever terminating with a hook registering with the lower part of the perforation at a point lying under the stationary pin with a vertical spacing with reference to said stationary pin slightly larger than the breadth of the rim of a correctly sized coin rim, a second lever pivotally secured to a second stationary point outside the perforated wall on the side of said wall facing away from the channel, the geometrical projection of said second point on the perforated wall lying between the projection of the first-mentioned stationary point on said perforated wall and the perforation in the latter, said second lever including an upper bent extension engaging a point of the first lever near the pivotal point thereof, a screw rigid with the lower end of the second lever, engaging the upper part of the perforation in coaxial registry with the stationary pin, the dropping of a coin between said pin and said screw urging transiently the screw aside and thereby shifting the levers in opposite directions with an amplification of the movement of the first lever to transiently engage the hook underneath the coin, said engagement of the hook being released only upon release of the screw returning under the action of gravity towards its inoperative position 50 upon registering of said screw with the main central thinner section of the coin of an acceptable type.

2. A device sensitive to a reduction in the height of rim of the coins inserted in automatic distribution machines, comprising two parallel walls defining between them a downwardly sloping channel for the insertion of the coins and of which one is provided with a short longitudinal perforation registering with the path of the coins dropping through the channel, a stationary pin carried by the other wall and facing the upper portion of the perforation in the first-mentioned wall, a first lever pivotally secured to a stationary point outside the perforated wall above the perforation on the side of said wall facing away from the channel, said lever terminating with a hook registering with the lower part of the perforation at a point lying under the stationary pin with a vertical spacing with reference to said stationary pin slightly larger than the breadth of the rim of a correctly

sized coin rim, a second lever pivotally secured to a second stationary point outside the perforated wall on the side of said wall facing away from the channel, the geometrical projection of said second point on the perforated wall lying between the projections of the first-mentioned stationary point on said perforated wall and the perforation in the latter, said second lever including an upper bent extension engaging a point of the first lever near the pivotal point thereof, a screw adjustably screwed into the lower end of the second lever, engaging the upper part of the perforation in coaxial registry with the stationary pin, said screw being shifted transiently by a small amplitude under the action of the dropping of a coin of a predetermined rim thickness, said shifting producing through the upper extension of said second lever a shifting of a larger amplitude and in the opposite direction of the first lever and of its hook, said screw being released at the end of the passage of the rim in front of it and the associated pin and screw allowing the free passage of coins thinner than normal between them.

3. A device sensitive to a reduction in the height of rim of coins inserted in automatic distribution machines, comprising two parallel walls defining between them a downwardly sloping channel for the insertion of the coins and of which one is provided with a short longitudinal perforation registering with the path of the coins dropping through the channel, a stationary pin carried by the other wall and facing the upper portion of the perforation in the first-mentioned wall, a first lever pivotally secured to a first pivot and adapted to oscillate in a plane inclined slightly with reference to the vertical and passing through a first stationary point outside the perforated wall above the perforation on the side of said wall facing away

from the channel, said lever terminating with a hook registering with the lower part of the perforation, a second lever pivotally secured to a second horizontal pivot and adapted to oscillate in a vertical plane parallel with the walls and passing through a second stationary point outside the perforated wall on the side of said wall facing away from the channel, the geometrical projection of said second point on the perforated wall lying between the projection of the first stationary point on said perforated wall and the perforation in the latter, said second lever including an upper bent extension engaging a third point on the first lever near the first pivot, a screw set in the lower end of the second lever, engaging the upper part of the perforation in coaxial registry with the stationary pin, the dropping of a coin between the pin and the screw urging transiently the screw aside and thereby shifting the levers in opposite directions with an amplification of the movement of the first lever to transiently engage the hook underneath the coin, said engagement of the hook being released only upon release of the screw returning under the action of gravity towards its inoperative position upon registering of said screw with the main central thinner section of a coin of an acceptable type.
